C. T. DANE,
CURTAIN STRETCHER,
APPLICATION FILED MAY 10, 1918.

1,314,574.

Patented Sept. 2, 1919.

UNITED STATES PATENT OFFICE.

CHRISTIAN T. DANE, OF BROOKLINE, MASSACHUSETTS.

CURTAIN-STRETCHER.

1,314,574.

Specification of Letters Patent. Patented Sept. 2, 1919.

Application filed May 10, 1918. Serial No. 233,668.

To all whom it may concern:

Be it known that I, CHRISTIAN T. DANE, a citizen of the United States, residing at Brookline, in the county of Norfolk and 5 State of Massachusetts, have invented new and useful Improvements in Curtain-Stretchers, of which the following is a specification.

This invention relates to an improved 10 curtain stretcher.

The object of the invention is to provide a light, cheap and simple device for holding curtains in extended position while they are drying after having been washed or 15 cleansed.

The object of the invention is further to provide a light framework which can be firmly fastened together so as to support any length or width of curtain in position 20 while drying and which, when not in use, can be folded in small space for storing or for shipment.

To these ends the invention consists in the combination and arrangement of parts 25 set forth in the following specification and particularly pointed out in the claims thereof.

Referring to the drawings:

Figure 1 is a front elevation of my im- 30 proved curtain stretcher.

Fig. 2 is a plan view of the curtain stretcher parts collapsed in readiness to be packed for storage or shipment.

Fig. 3 is a sectional elevation taken on 35 line 3—3 of Fig. 1.

Fig. 4 is a perspective view of the channel bracket which connects the upper horizontal bar to the vertical side bar.

Fig. 5 is a detail section taken on line 5—5 40 of Fig. 1.

Fig. 6 is a detail section taken on line 6—6 of Fig. 1.

Fig. 7 is a sectional plan taken on line 7—7 of Fig. 1.

Fig. 8 is a sectional elevation taken on 45 line 8—8 of Fig. 1.

Like numerals refer to like parts throughout the several views of the drawings.

In the drawings, 10 is an upper horizontal 50 bar, 11 a lower horizontal bar. 12 and 13 are vertical side bars. 14 is a vertical center bar.

The upper horizontal bar consists of two 55 parts 15 and 16 connected together by a hinge 17 and locked in extended position by a bolt 18 which is slidably mounted in guide

plates 19 and 20 on the part 15 and is adapted to engage a lock plate 21 on the part 16, thus locking the two parts 15 and 16 firmly in extended position. 60

The lower horizontal bar 11 consists of two parts 22 and 23 connected together by a hinge 24 fast to the lower sides of said parts 22 and 23, said parts being locked in extended position by a bolt 25 which is 65 slidably mounted in guide plates 26 and 27 on the part 22 and is adapted to engage a lock plate 28 on the part 23, thus locking the lower horizontal bar in extended position. 70

The center bar 14 is fastened to the reverse faces of the horizontal bars 10 and 11 by bolts 29 and thumb-nuts 30.

To the upper ends of each of the vertical side bars 12 and 13 is fastened a channel-shaped bracket 31 which has an upwardly extending right angled ear 32 and oppositely extending lateral arms 33. The upper ends of the side bars rest in the channel shaped portion of the brackets 31 and 75 are fastened thereto by screws extending through holes 34 in the flanges on the opposite side of said channel brackets. The right angle ear 32 projects upwardly on the reverse face of the upper horizontal 80 bar and forwardly over the upper edge of said horizontal bar while the arms 33 extend along the lower edge of said horizontal bar, thus firmly holding the bar on three sides thereof. The bar when located in the 85 proper position is clamped firmly to the bracket by a clamp bracket 35, see Figs. 1 and 3.

The central portion 36 of the lower horizontal bar 11 is thicker, preferably twice as 90 thick, as the opposite end portions 37 thereof and a shoulder 38 (see Fig. 7) is formed between each of the end portions 37 and the central portion 36.

A spacing block 39 is interposed between 100 the side bar 13 and the shoulder 38 and another similar spacing block is interposed between the side bar 12 and the shouldered central portion 36. This spacing block is provided with a pair of straps 40 through 105 which the end portion 37 projects, said spacing block thus being made slidable upon the end portion 37.

Pins 41 are provided adjacent the inner 110 edges of the horizontal bar and of the vertical side bars upon which the edges of the curtains are suspended. The upper hori-

zontal bar is divided into spaces by index lines and these lines are numbered, preferably, 24, 30, 36, etc. as shown in Fig. 1, 24 indicating the distance from the hinge 5 to the index line 24 and 36 indicating the distance from the hinge to the index line 36 and so on. The spaces between the lines 24, 30, 36, 42 etc. are subdivided into inch spaces. The vertical side bars are similarly 10 divided into six-inch spaces by index lines as indicated in Fig. 1 and these spaces are subdivided into inch spaces.

The lower horizontal bar 37 is shouldered as hereinbefore set forth at 38, said shoulders being each twenty-four inches from the 15 center of the hinge 24 or from the divisional line of the two parts of the horizontal bar.

The spacing blocks 39 are of different 20 lengths, the particular spacing blocks shown in the drawings being six inches in length.

The center bar 14 is provided with a series 25 of holes 42 to receive the bolt 29 of the lower horizontal bar 11, these holes being indicated by index lines and numerals, whereby said bar 11 is positioned at different distances from the horizontal bar 10.

The lower horizontal bar 11 is clamped to the side bars 12 and 13 by clamps 43.

It will be seen that the obverse faces of 30 the upper horizontal bar 10 and the vertical side bars 12 and 13 are flush with each other, while the obverse faces of the lower horizontal bar and the vertical side bars are substantially flush with each other.

35 The manner in which the device hereinbefore specifically described is used is as follows: The curtain is measured as to its length and width before it is washed and the frame of the stretcher is set to correspond with the size of the curtain to be stretched thereon. As shown in Fig. 1 the frame of the curtain stretcher is set to accommodate a curtain sixty inches long and thirty inches wide. The curtain is stretched 40 upon the device by inserting the pins 41 in the edges of the curtain and the curtain drying on said pins in extended position dries flat and smooth. While the curtain is drying the device is placed upon the floor, with 45 the upper horizontal bar leaning against the wall, while the lower ends of the side bars 12 and 13 and the center bar 14 rest upon the floor, and support the structure.

Assuming that it is desired to stretch a 50 curtain seventy-two inches long and thirty-six inches wide, the side bars 12 and 13 are released from the horizontal bars by releasing the clamps 35 and 43 and another six inch spacing block is slipped onto each end 55 of the lower horizontal bar 11 and pushed up against the spacing block 39 already thereon. The bolt 29 is withdrawn from the center bar 14 and slipped into a hole in the center bar 14 which is indexed 36. The side 60 bars are then clamped to the upper hori-

zontal bar with the inner edges thereof flush with the index line marked "36." The side bars are clamped to the lower horizontal bar with their inner edges against the ends of the second spacing blocks which have been 70 placed upon the end portions 37 of the lower horizontal bar and with the upper edge of the bar 11 in alignment with the index lines 36 on the bars 12 and 13. The device is now in position to be used to stretch a curtain 72 75 inches by 36 inches.

Other spacing blocks 1 inch, 2 inches, three 80 inches, et cetera, in length are provided so that any subdivisions of the spaces 24 to 30 or 36 and so on can be obtained.

85 The device is collapsed by removing the clamps 35 and 43 and the bolts 29. The slide bolts 18 and 25 are then slipped back out of engagement with the locking plates 21 and 28 and the upper and lower horizontal bars are then folded by swinging them on their hinges until their opposite end portions are brought together and the different parts are then packed in small space, as illustrated in Fig. 2.

90 Having thus described my invention, what I claim and desire by Letters Patent to secure is:

1. A curtain stretcher having, in combination, an upper horizontal bar, a lower 95 horizontal bar and two vertical side bars, a bracket fast to the upper end of each of said side bars, said bracket consisting of a channel portion adapted to receive the upper end of one of said side bars, a right angled 100 ear extending upwardly from said channel portion and adapted to receive said upper horizontal bar and arms extending in opposite directions from the upper end of said channel portion of said bracket and beneath 105 said upper horizontal bar.

2. A curtain stretcher having, in combination, an upper horizontal bar, a lower horizontal bar and two vertical side bars detachably fastened thereto, said lower horizontal bar having an end portion of less thickness than the central portion thereof and a spacing block interposed between one end of said central portion of said lower horizontal bar and one of said side bars.

115 3. A curtain stretcher having, in combination, an upper horizontal bar, a lower horizontal bar and two vertical side bars detachably fastened thereto, said lower horizontal bar having an end portion of less thickness 120 than the central portion thereof and a spacing block slidably mounted on said end portion and interposed between one end of said central portion and one of said side bars.

4. A curtain stretcher having, in combination, an upper horizontal bar, a lower horizontal bar and two vertical side bars detachably fastened thereto, said lower horizontal bar having an end portion of less thickness than the central portion thereof, whereby a 125 130

shoulder is formed at the junction of said end portion and central portion, and a spacing block interposed between said shoulder and one of said side bars and adjacent to said end portion.

5. A curtain stretcher having, in combination, an upper horizontal bar, a lower horizontal bar and two vertical side bars detachably fastened thereto, said lower horizontal 10 bar having an end portion of less thickness than the central portion thereof and a plu-

rality of spacing blocks of different lengths slidably mounted on said end portion and interposed between one end of said central portion and one of said side bars.

In testimony whereof I have hereunto set 15 my hand in presence of two subscribing witnesses.

CHRISTIAN T. DANE.
